US0D1035628S

(12) **United States Design Patent** (10) Patent No.: **US D1,035,628 S**
(45) Date of Patent: ** Jul. 16, 2024

(54) **HEADPHONE HOLDER**

(71) Applicant: **Sillber AG**, Basel (CH)

(72) Inventor: **Berend Frenzel**, Basel (CH)

(**) Term: **15 Years**

(21) Appl. No.: **35/515,850**

(22) Filed: **Dec. 7, 2022**

(80) **Hague Agreement Data**

Int. Filing Date: **Dec. 7, 2022**

Int. Reg. No.: **DM/225505**

Int. Reg. Date: **Dec. 7, 2022**

Int. Reg. Pub. Date: **Dec. 23, 2022**

(30) **Foreign Application Priority Data**

Jun. 7, 2022 (EM) 009053192-0001

Jun. 7, 2022 (EM) 009053192-0002

(57) **CLAIM**

The ornamental design for a headphone holder, as shown and described.

DESCRIPTION

1. Headphone Holder
- 1.1 : Front
- 1.2 : Back
- 1.3 : Left
- 1.4 : Right
- 1.5 : Top
- 1.6 : Bottom
- 1.7 : Perspective
- 1.8 : Perspective

1 Claim, 8 Drawing Sheets
